US00D861599S

(12) **United States Design Patent** (10) **Patent No.:** **US D861,599 S**
(45) **Date of Patent:** **** Oct. 1, 2019**

(54) **WIRELESS CHARGER**

(71) Applicant: **Samsung Electronics Co., Ltd.**, Suwon-si (KR)

(72) Inventors: **Eunha Choi**, Seoul (KR); **Jonhyuk Bae**, Seoul (KR); **Minki Ham**, Seoul (KR); **Namkyu Kim**, Seoul (KR)

(73) Assignee: **SAMSUNG ELECTRONICS CO., LTD.**, Suwon-si (KR)

(**) Term: **15 Years**

(21) Appl. No.: **29/640,605**

(22) Filed: **Mar. 15, 2018**

(30) **Foreign Application Priority Data**

Dec. 21, 2017 (KR) 30-2017-0060831

(51) **LOC (12) Cl.** **13-02**

(52) **U.S. Cl.**

USPC **D13/108**; D14/253

(57) **CLAIM**

The ornamental design for a wireless charger, as shown and described.

DESCRIPTION

FIG. 1 is a front perspective view of a wireless charger showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear perspective view thereof.

The dashed broken lines in the drawings illustrate portions of the wireless charger that form no part of the claimed design.

1 Claim, 8 Drawing Sheets
